UNITED STATES PATENT OFFICE

ARTHUR E. DAVY, OF BROCKTON, MASSACHUSETTS, ASSIGNOR TO HAMILTON-WADE COMPANY, OF BROCKTON, MASSACHUSETTS, A CORPORATION OF MASSACHUSETTS

FINISHING WELT AND METHOD OF MAKING THE SAME

Application filed January 20, 1930. Serial No. 421,886.

This invention relates to finishing welt or binding for use in upholstery or for finish or ornamental binding and the method of making the same. While my improved welt is adapted particularly for use in connection with the interior finish of automobiles, the invention is of more general application.

The purpose of my invention is to provide a composite finishing welt presenting a particularly attractive and symmetrical appearance and which may be readily and securely attached by headed fasteners which are concealed and protected by the welt.

In one aspect my invention consists in improvements in finishing welt of the type disclosed in application for United States Letters Patent of Albert L. Howard, Serial No.

413,771, filed December 13, 1929. As in the welt of that application, I contemplate a center or main bead movably secured in place, embellished with a lateral edge bead at one or both margins, the loose edges of the material being concealed. These lateral edges may or may not be colored to contrast with the main bead. An important feature of my invention consists in the construction and arrangement of the covering material for these beads wherein the loose edges of the covering are concealed in different positions,

facilitating the assembling operation and effecting a more nearly symmetrical appearance. This I am enabled to accomplish by attaching a sheathing strip for the main bead and a body strip for covering the lateral beads and forming the base, in superposed relation, directly to the under side of the main bead filler with finished surfaces facing each other and two of their edges approximately in registration. The sheathing

strip is then wrapped entirely around the main bead filler with its free edge extending below the filler. A lateral bead filler is surrounded by deflecting a portion of the body strip in a reverse angular direction from the direction of wrapping the sheathing strip. The free edge of the body strip may be then again deflected and concealed in registration with the free edge of the sheathing strip between the deflected portions of the body strip,

and locating each lateral edge of each strip in registration with the corresponding lateral edge of the other strip. Where a marginal bead is desired at both edges of the welt, the body strip is wrapped around a second lateral bead filler along the line of the last deflection.

In another aspect my invention consists in a welt constructed in two principal parts, a main bead and a base portion hingedly attached at one edge by means of two separate webbings of strip material connecting said bead along two separated parallel lines throughout the length of the bead, providing a more even support for the bead and maintaining it more uniformly in parallel relation to the base.

These and other features of the invention will be best understood and appreciated from the following description of a preferred embodiment thereof, selected for purposes of illustration and shown in the accompanying drawing, in which

Fig. 1 is a view in perspective of a central filler core with the sheathing and body strips attached;

Fig. 2 is a similar view showing one edge of the sheathing strip wrapped around the filler core;

Fig. 3 is a similar view showing the body strip partially folded;

Fig. 4 is a similar view of a completed finishing welt in the preferred form; and

Fig. 5 is a sectional view, on an enlarged scale, of the welt shown in Fig. 4.

A semi-circular central bead filler core 10 is disposed along the registering edges of a sheathing strip or covering 12 of flexible material superposed, with their finished surfaces facing each other, upon a body strip 14. A line of stitching 16 connects these two together, passing through the filler core adjacent to one edge thereof, although the exact location is of secondary importance only. The connecting stitching might well pass through any portion of the filler core but there are certain advantages which will appear more clearly hereinafter, in locating the line of stitching nearer that edge which is directed toward the central portions of the

superposed strips. The sheathing strip 12 is, according to the construction shown, narrower than the body strip. The dimensions are governed by the size of fillers and the proportions desired in the finished welting and can be adjusted in any suitable manner.

In the next step, the sheathing strip 12 is wrapped entirely around the filler 10 with its extending free lateral edge disposed beneath the registering edges which are attached to the filler. The body strip is then deflected or folded downwardly and beneath the filler 10 through an angle of approximately 180°, enfolding a lateral bead filler cord 18. A second lateral bead filler cord 20 may be disposed at the opposite side of the central bead and the free lateral edge 22 of the body strip 14 may then be folded about the filler cord 20 through another angle of approximately 180°, concealing the free edge 22 between the depending sides of the portion of the body strip which is folded about the filler cord 18. Thus, the body strip is deflected in an opposite angular relation to the direction of wrapping of the sheathing strip about the filler 10, exposing the finish of both strips at all outside surfaces, and finally bringing the extending edges of the strips with their finished surfaces again into contact.

The parts are maintained in place when once formed in position by two lines of stitching 24 and 26, passing through the strips between the central filler 10 and the lateral cords of the beads at each side of the central core. The line of stitching 24 passes through the two depending sides of the portion of the strip folded about the filler cord 18 and through the registering edges 17 and 22 of the two strips. The stitching 26 serves to hold the filler cord 20 in place as well as definitely to locate the lateral edge of the welting.

The position of the parts occupied in the completed welting is indicated more clearly in Fig. 5, it being apparent that corresponding lateral edges of both strips are in registration and that these edges are alternately interleaved and concealed between the folded portions of the strips. These edges are not concentrated along either edge of the welting but extend sufficiently toward the center line of the welting to obviate an unsymmetrical appearance. A space 28 is provided between the filler cord 10 and the lower pass of the sheathing strip 12, permitting a certain amount of clearance for projections produced by the heads of fastening devices, or otherwise.

It will be noted that the central main bead formed by the filler 10 is attached to one edge of the base portion formed by the body strip, by means of two separate webbings of strip material connecting said edge of the base portion with the bead respectively along lines

longitudinally of and at the opposite edges of the bead. Thus, the filler 10 is connected to the lateral edge of the base containing the filler cord 18 by a flange or feather 30 of the body strip and a portion 32 of the sheathing strip, the feather 30 being attached along the line of stitching 16 while the portion 32 of the sheathing strip is in close contact along the line of the right edge of the filler 10 effectively forming a connection along that edge. By connecting the main bead along two lines, a more symmetrical appearance results and the lower edge of the filler core is maintained in more uniformly parallel relation with the base. The two strips of sheet material may be provided with differently finished surfaces to contrast with each other in the completed welt and also to provide different wearing qualities, according to the use to which the welt is intended.

The filler core 10 may be composed of some fibrous or woven material for preventing the stitching from pulling through. Rubber or other composition with a fibrous reinforcing member could also be employed. The sheathing and body strips 12 and 14 may be artificial or genuine leather or other sheet material.

It has been found that the bead portion of welting constructed according to the methods herein described will lie unusually close within the space between the upstanding lateral beads, even with the use of fastenings or other devices having projecting surfaces between the bead and the base portion. From a mechanical standpoint, the welding presents every advantage of convenience in attachment and durability in wear.

Having thus described my invention, what I claim as new and desire to secure by Letters Patent is:

1. A finishing welt having central and lateral bead fillers, a sheathing strip and a main body strip, having registered edges attached to one edge of said central filler, said sheathing strip being wrapped about said central filler and said main strip being wrapped about said lateral filler, the other edge of the sheathing strip being concealed between two portions of the main strip, and a line of stitching passing through the main strip and said edge of the sheathing strip.

2. A finishing welt having central and lateral bead fillers, a plurality of superposed strips with edges attached to said central filler, the extending edges of said strips being wrapped in opposite directions, one about the central filler through an angle of substantially 360 degrees and the other about the lateral filler through an angle of substantially 180 degrees, forming a double thickness of strip material depending from said lateral filler, and the extending edge of the strip which is wrapped about said central filler being concealed and fastened between said double thicknesses by a line of stitching.

3. A finishing welt having central and lateral bead fillers, a plurality of strips with registering edges attached to said central filler, the extending edges of said strips being wrapped in opposite directions, one about the central filler and the other about the lateral fillers, said lateral fillers being positioned one at either side of said central filler and the extending edges terminating in registration and being concealed beneath the first mentioned edges.

4. A finished well having central and lateral bead fillers, a plurality of strips with registering edges attached to said central filler, the extending edges of said strips being wrapped in opposite directions, one about the central filler and the other about the lateral fillers, said lateral fillers being positioned one at either side of said central filler and the extending edges terminating in registration and being concealed beneath the first mentioned edges and secured in place by stitching passing through said strips between said central and lateral fillers on each side of the central filler.

5. A finishing welt comprising a main bead and a base portion hingedly attached along one edge thereof by means of two separate webbings of strip material connecting said base portion with said bead respectively along two relatively spaced parallel lines longitudinally of and adjacent to the bead.

6. The method of forming a finishing welt which comprises attaching superposed strips of material having finished surfaces facing each other to a main bead filler, wrapping one strip completely around the filler exposing its finished surface, deflecting another of said strips in a reverse direction to form a fold around another filler and fastening the extending edge of the first strip within the depending sides of the fold.

7. The method of forming a finishing welt which comprises attaching superposed strips of material having differently finished surfaces facing each other, to a main bead filler, wrapping one strip completely around the filler in a manner to expose its finished surface and deflecting in a reverse direction another of said strips through substantially 360 degrees forming a flattened envelope about lateral bead fillers disposed in the edges of said envelope.

8. The method of forming a finishing welt which comprises attaching two superposed strips of material having differently finished surfaces facing each other, to a main bead filler, wrapping one strip completely around the filler in a manner to expose its finished surface, folding the other strip to form a base portion, and extending the free edge portions of said strips in the same direction and securing them together with their finished surfaces in face to face contact.

9. A finishing welt comprising main and

lateral beads, covering strips therefor one folded to cover said main bead and another folded to cover said lateral bead and each having a free outwardly extending edge portion remaining after covering its bead, said free edge portion of the main bead strip being folded beneath the main bead and the free edge portion of the other strip being folded therebeneath to form a base portion and doubled back upon itself beneath the main bead and adjacent to the free edge portion of the main bead strip, whereby both free edges of the strips are interleaved and concealed in the welt above said base portion.
